US00D950833S

(12) **United States Design Patent** (10) **Patent No.:** **US D950,833 S**
Stanley (45) **Date of Patent:** **** May 3, 2022**

(54) **HORTICULTURE GROW LIGHT**

- (71) Applicant: **HGCI, Inc.**, Las Vegas, NV (US)
(72) Inventor: **John Stanley**, Vancouver, WA (US)
(73) Assignee: **HGCI, Inc.**, Las Vegas, NV (US)
(**) Term: **15 Years**
(21) Appl. No.: **29/728,883**
(22) Filed: **Mar. 23, 2020**

Related U.S. Application Data

- (63) Continuation of application No. 29/682,706, filed on Mar. 7, 2019, now Pat. No. Des. 879,365, which is a continuation of application No. 29/617,484, filed on Sep. 14, 2017, now Pat. No. Des. 843,049.

Primary Examiner — Lauren D McVey*Assistant Examiner* — Justin A Johnson(74) *Attorney, Agent, or Firm* — Ulmer & Berne LLP(57) **CLAIM**

The ornamental design for a horticulture grow light, as shown and described.

DESCRIPTION

FIG. 1 is a perspective view of a horticulture grow light, as viewed from below, showing my new design;

FIG. 2 is a perspective view of the light shown in FIG. 1, as viewed from above;

FIG. 3 is a left side view of the light shown in FIG. 1;
FIG. 4 is a right side view of the light shown in FIG. 1;
FIG. 5 is a front elevation view of the light shown in FIG. 1;

FIG. 6 is a rear elevation view of the light shown in FIG. 1;
FIG. 7 is a top plan view of the light shown in FIG. 1; and,
FIG. 8 is a bottom plan view of the light shown in FIG. 1. The broken lines immediately adjacent to the shaded areas depict the bounds of the claimed design, while all other broken lines are directed to environment. The broken lines form no part of the claimed design.

1 Claim, 8 Drawing Sheets# US D950,833 S
